UNITED STATES PATENT OFFICE.

GOTTFRIED M. LIEB, OF NEWARK, NEW JERSEY, ASSIGNOR TO JOHN A. LIEB, OF SAME PLACE.

DESIGN FOR AN ORNAMENTAL CHAIN.

SPECIFICATION forming part of Design No. 13,318, dated September 26, 1882.

Application filed August 30, 1882. Term of patent 7 years.

To all whom it may concern:

Be it known that I, GOTTFRIED M. LIEB, a citizen of the United States, residing at Newark, in the county of Essex and State of New Jersey, have invented and produced a new and original Design for Ornamental Chains, of which the following is a specification, reference being had to the accompanying drawings.

In the drawings, Figure 1 is a side view of a piece of a chain containing my design. Fig. 2 is an end view thereof. Fig. 3 is a face view of one of the links of the chain.

Similar letters indicate corresponding parts.

The form of the links A of the chain is shown in Fig. 3. The link is composed of two rectangles, a, joined by the diamond b, leaving an opening or cleft, c, between them. In each rectangle is a slot or aperture, d. When joined to form a chain the links A are arranged in pairs, the links of each pair being arranged obliquely to one another in a direction lengthwise of the chain, and the alternate pairs of links being arranged at approximately a right angle to the intermediate pairs, thus forming a chain approximately quadrangular in transverse sec-

tion. The links are secured by inserting the rectangles a a of each pair of links into the slots or apertures d of the succeeding pair of links.

What I claim as new, and desire to secure by Letters Patent, is—

1. The design for a chain-link, substantially as herein shown and described, consisting of the two rectangles a, having slots d joined by the diamond b, and having a cleft, c.

2. The design for a chain, consisting of pairs of links A of the form of two rectangles, a, having slots or apertures d joined by the diamond b, and having a cleft, c, the links of alternate pairs being approximately at right angles to the links of intermediate pairs, substantially as herein shown and described.

In testimony whereof I have hereunto set my hand and seal in the presence of two subscribing witnesses.

GOTTFRIED M. LIEB. [L. S.]
